PLASTER EDGE STRIPS

Roy E. Tatum, Detroit, Mich., assignor to Blakely Products Company, Warren, Mich., a corporation of Michigan

Filed Jan. 4, 1967, Ser. No. 607,284
2 Claims. (Cl. 52—367)

ABSTRACT OF THE DISCLOSURE

An extruded edge strip to be secured to a roughly finished wall to guide and establish the thickness of a subsequently applied coating of plaster-like material and to provide a straight edge for such coating. A modified edge strip may be used to simulate a caulked joint in the plaster-like coating.

Cross-reference to related application

This application is a continuation-in-part of my co-pending application, Ser. No. 382,138, filed July 13, 1964, now United States Patent No. 3,307,313.

Background and summary of invention

In applying relatively thick finished coatings of plaster or plaster-like material to wall surfaces it is extremely difficult and time consuming to form straight, sharp corners and edges, as well as to maintain a uniform coating thickness. This is particularly true where the coatings are formed of such plaster-like materials as small pieces and chips of stone mixed with plastic resins or with plaster.

It is therefore an object of this invention to provide edge strips which form straight edges or joints, during application of relatively thick coatings of plaster-like material upon wall surfaces, and which strips also function to gauge the thickness of such coatings.

It is a further object of this invention to provide an edge or joint strip which has a portion capable of receiving caulking material to permit the simulation of a conventional caulked joint in a plaster-like wall surface.

Brief description of the drawings

FIG. 1 is an elevational view of a portion of the wall surface, prior to coating having various edge strips arranged thereon.

FIG. 2 is an enlarged cross-sectional view of a pair of joint strips taken in the direction of arrows 2—2 of FIG. 1, with the finished coating in place.

FIG. 3 is a view similar to FIG. 2, but illustrating a modified form of joint strip.

Detailed description

FIGS. 1 and 2 illustrate the front wall surface 10 of a rough wall construction 12, which may be of rough plaster, masonry or the like. A relatively thick, finished wall coating 14 is applied to surface 10 of rough wall 12. The coating may be approximately $\frac{1}{16}$ to $\frac{1}{4}$ inch in thickness and may be formed of conventional finish plaster or of one of the many available plaster-like finishing materials, such as a mixture of small chips or pieces of stone and suitable plastic resin or plastic.

Wall surface 10 is prepared for the finished coating 14 by having mounted thereon a plurality of edge strips. To edge and gauge the thickness of the plaster on both sides of a wall corner, a corner strip 16 may be employed. Similarly, at the lower extremity of the finished coating surface, base strip 18 is utilized, while at the top of the wall an upper edge strip 20 is applied. Strips 16 and 20 are more fully disclosed in my above identified parent application, while strips 18 are described more fully in another co-pending application, Ser. No. 607,285, filed Jan. 4, 1967.

2

At the joint in the finished coating, a pair of identical joint strips 22 having caulking 24 interposed therebetween is mounted.

Each of these edge strips has its own unique cross-sectional configuration to provide the desired edging and gauging function at the particular wall location. These edge strips may be roll-formed or formed of metal or plastic extrusions. The finished wall coating 14 is applied after the strips have been arranged and secured to wall surface 10.

Joint strips 22 are more fully illustrated in FIG. 2. Each of these strips has a generally L-shaped configuration, with a long strip portion 26 having an inner face 28 adapted to be applied to wall surface 10 and an outer face 30. The other leg of the L comprises a flange portion 32 with an end face 34 perpendicular to inner face 28, a short outer face 36, and an inclined face 38 interconnecting faces 36 and 30.

The strip portion 26 of joint strips 22 is further provided with a number of spaced openings or slots 40. An initial coating of cement or plaster is locally applied to wall surface 10 and strips 22 are applied over this initial coating before it has completely dried. Some of this cement or plaster enters and extends through opening 40, thereby anchoring the strip to the wall. Finish coating 14 is thereafter applied using flange outer face 36 as a guide to gauge the thickness of the coating. Caulking 24 is then applied to the gap left between the two adjacent joint strips 22 to complete the installation.

It is to be understood that joint strip 22 may be used singly as an edge strip if desired, and need not be limited to use in pairs at joint locations.

A modified form of joint strip is illustrated in FIG. 3. This joint strip 42 is generally F-shaped in cross-sectional configuration, having a strip portion 44 adapted to be applied to wall surface 10, an end flange 46 and a second flange 48. The length of flange 48 is such that its outer edge projects the same distance from the wall surface as does flange 46. Openings or slots 50 are spaced along the length of strip portion 44 for the same purpose as slots 40 in the embodiment of FIG. 2. It can be seen that when caulking is applied to the space between flanges 46 and 48, the effect of two panels of coating 14 separated by caulking 24 is created. This embodiment offers the advantage over the embodiment of FIG. 2 requiring only single strip to be applied at each joint location on the wall, instead of two L-shaped strips.

This invention may be further developed within the scope of the following claims. Accordingly, the above description is to be interpreted as illustrative of only two operative embodiments of this invention, and not in a strictly limited sense.

I now claim:

1. An extruded aluminum edge strip having a long, uniform, solid cross-section for edging a joint in a relatively thick coating of plaster-like material applied upon a wall surface, comprising in cross-section:
  - a thin, narrow strip portion having a flat wall surface contacting inner first face and an opposite flat outer second face, shorter in length than said first face and arranged in a plane converging toward said inner face so that said strip portion is tapered in cross-section with one narrow edge where said first and second faces intersect and an opposite wide edge;
  - a continuous, narrow, flange portion integrally joined with said strip portion at said wide edge, said flange portion comprising a third flat end face, projecting perpendicularly outwardly beyond a projection of said second face from said strip inner first face at said wide edge, a narrow fourth flat outer face parallel to said first face and extending generally toward said

strip portion narrow edge from the outer end of said third face, and a fifth flat face interconnecting each of said second and fourth faces at an obtuse angle; 5
 a second continuous narrow flange substantially parallel with said first flange portion and integrally joined with said strip portion at a point spaced slightly from said first flange portion so as to form a generally F-shaped cross-section, the second flange being of a length such that its outer edge projects the same distance from said first face as said first flange portion; 10
 wherein said strip portion may be applied to a wall surface and thereafter covered by said coating with said third face edging said coating and said fourth face gauging the thickness of said coating;
 2. A pair of identical extruded aluminum edge strips, 15
 each comprising a long, uniform, solid cross-section for edging a joint in a relatively thick coating of plaster-like material applied upon a wall surface, comprising in cross-section;
 a thin, narrow strip portion having a flat wall surface 20
 contacting inner first face and an opposite flat outer second face, shorter in length than said first face and arranged in a plane converging toward said inner face so that said strip portion is tapered in cross-section with one narrow edge where said first and second faces intersect and an opposite wide edge;
 a continuous, narrow, flange portion integrally joined with said strip portion at said wide edge, said flange portion comprising a third flat end face, projecting 25
 perpendicularly outwardly beyond a projection of said second face from said strip inner first face at said wide edge, a narrow fourth flat outer face paral-

lel to said first face and extending generally toward said strip portion narrow edge from the outer end of said third face, and a fifth flat face interconnecting each of said second and fourth faces at an obtuse angle; 5
 wherein said strip portion may be applied to a wall surface and thereafter covered by said coating with said third face edging said coating and said fourth face gauging the thickness of said coating; 10
 said strips being each applied to an unfinished wall surface so as to be parallel to each other, and oriented so that said flange portions of said first and second strips are adjacent but spaced slightly from each other thereby to establish a gap between the strips defined by said third end faces of each of said two strips, said gap to be filled with caulking material to simulate a conventional caulked joint.
